(57) **CLAIM**

The ornamental design for an interface and bezel for uninterruptible power supply, as shown and described.

DESCRIPTION

FIG. 1 is a perspective view of an interface and bezel for uninterruptible power supply design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof, shown in environmental use.

The broken lines shown represent unclaimed subject matter and form no part of the claimed design.
